UNITED STATES PATENT OFFICE.

JOSEPH A. MEYERS, OF LOS ANGELES, CALIFORNIA, ASSIGNOR OF ONE-HALF TO SOL SHAPIRO, OF LOS ANGELES, CALIFORNIA.

DESIGN FOR A RING.

54,112.

Specification for Design.

Patented Nov. 4, 1919.

Application filed December 7, 1918. Serial No. 265,999. Term of patent 14 years.

To all whom it may concern:

Be it known that I, JOSEPH A. MEYERS, a citizen of the United States, residing at Los Angeles, in the county of Los Angeles and State of California, have invented a new, original, and ornamental Design for a Ring, of which the following is a specification, reference being had to the accompanying drawing, forming part thereof.

In the drawing,

Figure 1 is a face view of a ring embodying my invention; and,

Fig. 2 is a side elevation partly in section.

I claim:

The ornamental design for a ring as shown.

JOSEPH A. MEYERS.

Witnesses:

LOUIS W. GRATZ,
DOROTHY MOORHOUSE.
